UNITED STATES PATENT OFFICE

ROBERT L. DURFLINGER, OF INDIANAPOLIS, INDIANA

WINDOW-SCREEN HANGER

Application filed June 24, 1929. Serial No. 373,148.

This invention relates to window screens and particularly to means for holding the screens in position.

The primary objects of the invention reside in means permitting the screen to be easily placed in position and removed therefrom whereby the screen may be handled entirely from within a room; in means that may be readily attached to window frames now in existence without having to alter the frame or the screen in any manner; in means that may permit the raising and lowering of the screen even though the screen may be warped to some extent; and means that may be manufactured at a very low cost of production and of such type that skilled labor is not required for its installation.

These and other objects will become apparent in the following description of the invention which is made in reference to the accompanying drawing, in which—

Fig. 1 is an outside elevation of a window frame to which my invention has been applied;

Fig. 2, a vertical section on the line 2—2 in Fig. 1;

Fig. 3, a fragmentary elevation of a screen rail with an attaching guide;

Fig. 4, a side elevation of the guide as shown in Fig. 3;

Fig. 5, a horizontal section on the line 5—5 in Fig. 4;

Fig. 6, a side elevation of a lower attaching guide;

Fig. 7, a fragmentary elevation of a screen showing a modified form of a retaining guide; and

Fig. 8, a horizontal section on the line 8—8 in Fig. 7.

Like characters of reference indicate like parts throughout the several views in the drawing.

Referring first to Figs. 1 and 2 wherein is formed a common type of window frame 10 having the upper sash 11 and the lower sash 12 here shown in a raised or open position, I mount a window screen 13 between the outside sash retaining strips 14 and 15. To hold the screen 13 in position, I employ

a pair of top guides 16 and a pair of lower guides 17.

Referring now to Figs. 4, 5 and 6, the upper guide 16 consists essentially of a short length of channel bar having a hole 18 formed centrally through the web. The lower guide 17 is exactly the same as the guide 16 with the exception that instead of one hole, each guide 17 is provided with the two holes 19 and 20. One each of the guides 16 is secured to the strips 14 and 15 respectively by passing a wood screw 21 through the hole 18 of the guide. Since there is but one screw in each of the guides 16 these guides may be rocked about the screws 21. These guides 16 are positioned at distances above the sill of the frame so as to be substantially near the top end of the screen 13 when the screen rests by its lower rail on the sill.

A guide 17 is attached to each of the strips 14 and 15 above the sill of the frame, as indicated in Fig. 1, by passing wood screws through each of the holes 19 and 20, whereby both guides 17 are held in fixed positions so that they may not be rocked.

All of the guides 16 and 17 are mounted on the strips 14 and 15 so that the screen 13 may slide freely therebetween by having its stiles 22 and 23 slidably engaged between the legs of the guides.

Assuming the screen 13 to be positioned in the frame as indicated in Fig. 1, the screen 13 may be removed therefrom by raising it slightly to the position as indicated by the dash-dot lines, Fig. 1, whereupon the lower end of the screen 13 is pulled inwardly to within the room as indicated in Fig. 2, by rocking the screen as held by the upper guide 16 about the screws 21. The screen may then be pulled downwardly to slide between the guides 16 in the direction as indicated by the arrow, Fig. 2. In the reverse fashion, the screen may be replaced from within the room by first inserting it between the guides 16, then rocking the screen to a vertical position, and finally lowering the screen to have it pass between the guide 17.

In the foregoing description, the stiles 22 and 23 have been shown as of the usual type. In those stiles where a longitudinal groove is

provided in the outer edges, the guide 24, Figs. 7 and 8, may be employed in place of the guides 16 and 17, so as to provide a concealed construction. In this modified form as shown in Figs. 7 and 8 the guide 24 is substantially V-shaped in cross section, the upper guide having a single screw 25 passed centrally therethrough so as to pivotally retain the guide 24 against the face of the strip

14. The guide 24 is adapted to fit slidably within the longitudinal groove 26 of the stile 27 of the screen so that the screen may be lowered and raised over the guide 24 and also be rocked laterally. The lower guide 24' is exactly the same as the upper guide 24, but is fixed in position against the strip 14.

While I have here shown my invention in the best form now known to me it is obvious that many structural changes may be made in that form without departing from the spirit of the invention, and I therefore do not desire to be limited to that precise form any more than may be required by the following claims.

25 I claim:

1. The combination of a window screen, a pair of upper guides adapted to be mounted on a window frame, a pair of lower guides adapted to be mounted on the frame, said guides being formed to engage the stiles of the screen to permit said screen to be raised and lowered vertically therebetween, said upper guides having means to secure them pivotally to the frame to permit said screen to be rocked normally of the frame when engaged between said upper guides only.

2. In a window screen construction, a pair of guides adapted to be pivotally attached to the window frame and to receive the screen slidably thereon, and a second pair of guides adapted to be fixed to the frame adapted to receive said screen slidably therein while said screen is received by said first guides.

3. In the combination of a screen, a guide adapted to be pivotally secured to one side of a window frame, a second guide adapted to be pivotally secured to the opposite side of the window frame, both of said guides being mounted on the frame to be slidably engaged by said screen by its sides substantially near its top, a third guide adapted to be fixed to the window frame vertically below said first bracket, and a fourth bracket adapted to be fixed to the window frame vertically below said second guide, said third and fourth guides being formed to removably engage said screen and hold said first and second guides against rotation by said screen being engaged therebetween.

60 4. In a window screen construction, screen attaching means comprising two vertically spaced apart guides adapted to be mounted on each side of a window frame, each of said guides being adapted to engage both front and back faces of the sides of a screen and

the upper ones being pivoted to the window frame.

5. In a window screen construction, screen attaching means comprising two vertically spaced apart guides adapted to be mounted on each side of a window frame, each of said guides being adapted to engage the sides of a screen, the upper of said guides being pivoted to the frame.

In testimony whereof I affix my signature.

ROBERT L. DURFLINGER.
